US00D693349S

(12) **United States Design Patent**
Morgan et al.

(10) **Patent No.:** **US D693,349 S**
(45) **Date of Patent:** **** Nov. 12, 2013**

(54) **INTERFACE**

(75) Inventors: **Michael Gene Morgan**, Los Altos Hills, CA (US); **Paul Thomas McParland**, Saratoga, CA (US); **Mu-Jung Chen**, New Taipei (TW); **Ming-Hsueh Tsai**, Taipei (TW)

(73) Assignee: **Seagate Technology LLC**, Cupertino, CA (US)

(**) Term: **14 Years**

(21) Appl. No.: **29/388,316**

(22) Filed: **Mar. 28, 2011**

(51) **LOC (9) Cl.** **14-02**

(52) **U.S. Cl.**

USPC **D14/434**

(58) **Field of Classification Search**

USPC D14/432-434, 314, 204, 420-421, 447, D14/217, 356-358, 140, 142; D13/107-108, 146; D8/373; 248/346.03, 176.1; 361/679.43; 320/109, 112-115; 710/15, 303; 455/557; 439/347, 534

(57) **CLAIM**

The ornamental design for an interface, as shown and described.

DESCRIPTION

FIG. 1 is a front perspective of an interface showing my new design;

FIG. 2 is a rear view thereof;

FIG. 3 is a top view thereof;

FIG. 4 is a front view thereof;

FIG. 5 is a bottom view thereof; and,

FIG. 6 is a side view thereof, the opposite side view being a mirror image.

The broken lines showing a cartridge and connector are for environmental purposes only and form no part of the claimed invention.

1 Claim, 2 Drawing Sheets
